UNITED STATES PATENT OFFICE.

JOHN WILLIAM THRUSH, OF KEYSER, WEST VIRGINIA.

PLOW.

SPECIFICATION forming part of Letters Patent No. 634,740, dated October 10, 1899.

Application filed May 25, 1899. Serial No. 718,184. (No model.)

To all whom it may concern:

Be it known that I, JOHN WILLIAM THRUSH, a citizen of the United States, residing at Keyser, in the county of Mineral and State of West Virginia, have invented certain new and useful Improvements in Plows; and I do declare the following to be a full, clear, and exact description of the invention, such as will enable others skilled in the art to which it appertains to make and use the same.

The invention relates to certain novel improvements in plows and cultivators; and the object is to improve and simplify the construction and increase the utility and efficiency of the implement.

To this end the invention consists in certain features of construction and combination of parts, which will be hereinafter fully described and claimed.

In the drawings, Figure 1 is a perspective view of my improved plow or cultivator. Fig. 2 is a top plan view. Fig. 3 shows one manner of adjusting the plow. Fig. 4 shows the manner of adjusting the cultivator for plowing corn.

In the drawings, 1 denotes a clevis having three ears 2, 3, and 4, in which the beams 5, 6, and 7, respectively, are pivoted, and this clevis is formed with a slot 8 to receive the coupling-link 9, in which the single or double tree 10 is pivoted. Each beam is provided with a standard 12, the lower end of which carries the usual shovel-point 13.

14 14 denote X-shaped braces connecting the standards, the outer ones and the bottom part of the central one being provided with eyebolts 15 15 to receive the contiguous ends of the braces 14, the inner upper ends of which are journaled in a slotted bracket 16, having a sliding engagement with the central standard by means of the screw-bolts 17 17.

18 denotes a U-shaped bracket fixed to the central beam to receive the forward ends of the handle-bars 19 19, which are supported on the center standard by the transverse brace 20 and the V-shaped brace 21. A second V-shaped brace 22 also connects the handles

with the center beam, and the upper ends of this latter brace terminate in lateral ears 23 23, which rest upon suitable angle-brackets 50 50, fixed to the outside standards.

25 25 denote lateral bracket-arms fixed to the opposite sides of the central beam and which alternately engage the guard-shoes 26 26, fixed to the inside face of both of the outside beams, as shown, and which serve as guards for the forward ends of the beams. The upper ends of the outside standards are formed with notches 27 27 to receive the handles, which are removably secured thereto by 60 the hooks and staples 28 29, according to the position in which the plow is adjusted.

30 denotes an extra clevis which is used in place of the clevis 1, and when so employed the two outside standards are on a transverse 65 line and the central standard extends some distance to the rear, so that when plowing corn the two outside shovel-points form a furrow near the corn-row and the rear shovel-point splits the center.

It will of course be understood that various changes in the form, proportion, and the minor details of construction may be resorted to without departing from the spirit or sacrificing any of the advantages of this invention. 75

Having thus described the invention, what is claimed, and desired to be secured by Letters Patent, is—

A plow comprising a clevis, the three plow-beams pivoted thereto, and provided with the standards and shovel-points, the X-shaped braces connecting said standards, the handles attached to the center beam and standard, and means for locking the beams in advance of each other, substantially as and for the 85 purpose set forth.

In testimony whereof I have hereunto set my hand in presence of two subscribing witnesses.

JOHN WILLIAM THRUSH.

Witnesses:

A. H. METCALFE,
W. H. MARKWOOD.
